RATCHET HANDLE

Richard W. Vosper, Essex, Conn.

Application June 14, 1946, Serial No. 676,827

3 Claims. (Cl. 192—43.2)

1

This application is a continuation-in-part of my copending application Serial Number 578,479, filed February 17, 1945.

This invention relates generally to operating handles for hand tools and more particularly to ratchet handles.

A primary object of the invention is to provide an improved handle for hand tools having improved operating characteristics.

Another object of the invention is to provide a detachable ratchet handle for tool heads whereby the hand operation of such heads is facilitated.

A further object of the invention is to provide a detachable ratchet handle for use with tool heads whereby by the use of heads having uniform hubs or the employment of adapters, heads of a wide range of types and sizes are made interchangeable in an improved hand operated ratchet tool.

An additional object of the invention is to provide a detachable ratchet handle of inexpensive and rugged construction which is particularly suited for hand operated threading tools.

Other objects and features of the invention will appear hereinafter in the detailed description and be particularly pointed out in the appended claims.

In the drawings, illustrating a preferred embodiment of the invention:

Figure 1 is an elevational view of the ratchet handle.

Figure 2 is a vertical sectional view taken along the lines 2—2 of Figure 1, showing the handle applied to a die head.

Figure 3 is a side elevational view of the hub of a tool head.

Figure 4 is a vertical sectional view taken along the lines 4—4 of Figure 3.

Figure 5 is a front elevational view of an adapter for use with the tool heads having hexagonal hubs.

Referring now in detail to the drawings, in which like reference characters indicate like parts, the improved ratchet handle comprises a housing, casing or body portion 1. The upper portion of the housing is formed as a sleeve, collar or socket 2 which is preferably cylindrical in shape and adapted to slidably receive or embrace the correspondingly shaped hub or neck 3 of a tool head 4 within the sleeve opening 5.

Extending downwardly from the sleeve, substantially at right angles to its axis, is a stem, shaft or lever arm 6. The stem is preferably hollow throughout its entire length, with an axial 55

2

bore or hollow interior 7 opening at its upper end into the interior of the sleeve 2. Intermediate its ends the bore is interrupted by an inwardly projecting circular flange or rib 8, which divides the bore into upper and lower preferably cylindrical connected chambers, designated as 9 and 10, respectively. The lower chamber or downwardly opening pocket 10 is desirably of greater diameter than the upper chamber.

10 A rugged handle of adequate strength may be provided by shaping the stem in the manner shown in the drawings. As there illustrated, the exterior of the stem is substantially elliptical in cross section with its major dimension crosswise of the axis of the sleeve 2. The major dimension is approximately equal to the outside of the sleeve at the stem's upper extremity and gradually decreases toward the lower end of the stem. At its juncture with the sleeve the stem 15 has a pair of horns or extensions 11 which partly embrace the sleeve. The minor dimension of the stem is substantially uniform for the length of the upper chamber 9, thereafter flaring to provide sufficient wall thickness in the housing 20 around the lower chamber 10.

The illustrated configurations of the sleeve and stem not only provide a housing of adequate strength but particularly adapt the housing to be formed by casting, thus enabling the housing 30 to be cast in one piece with consequent saving in cost.

A pawl or ratchet of the plunger type 12 seats or fits within the upper chamber 9 in the stem. The upper end of the pawl is formed as a conventional one-way beveled tooth or prong 13 which normally extends into the sleeve opening 5. The lower end of the pawl rests or rides on a coil spring or other resilient means 14, the latter being housed or supported in a removable 35 spring container or housing 15. The container is preferably a cylinder closed at its lower end and having its upper end flanged outwardly to form a lip 16 which is carried on and engages the upper face or shoulder 17 of the rib 8 on the inner wall of the stem. The lower portion or shank 18 of the pawl is of reduced section to enable it to be slidably accommodated within the spring container 15.

In line with the upper edge of the spring container and for a substantial distance thereabove the stem is slotted along its minor dimension to provide a slot, opening or passage 19 extending through the opposite walls of the stem. Within the slot rides a preferably cylindrical control knob or collar 20 having a knurled outer surface,

the exposed portions of which are flush with the exterior of the stem. The knob encircles or collars the pawl 12 above its shank and is attached thereto by a pin or other suitable means 21. Turning or twisting of the knob thus turns the pawl and controls the engaging or driving direction of the pawl tooth 13. The knob not only serves as a turning or direction control for the pawl but, by abutting against the upper and lower walls respectively of the slot 19, limits the movement of the pawl longitudinally or axially of the stem. The knob is urged upwardly by the spring 14, and normally abuts the upper end of the slot, the tooth 13 then extending within the sleeve 5. The height of the slot relative to the knob is such that when the knob is pressed against the spring into engagement with the lower walls of the slot, the tooth is withdrawn from the sleeve opening into the upper chamber 9 in the stem.

To lock the pawl against turning, grooves or notches 22 are cut into the upper walls 19 on either side of the stem for normally receiving a pair of keys or detents 23 formed in and projecting above the upper face of the knob. Normally locking the pawl in forward or reverse position the keys are disengaged when the knob is depressed, permitting the knob to be turned. As illustrated in Figure 1, the detents 23 are of greater height above the upper face of the knob 20 than that portion of the prong 13 projecting into the sleeve opening 5. Consequently on depression of the pawl 12 against the spring 14 through the knob sufficiently to release the detents from the locking notches 22, the prong 13 is withdrawn into the stem 6, clearing the sleeve opening. Merely by partial rotation of the knob it is then possible to maintain the pawl in withdrawn position through abutment of the detents against the upper wall of the slot 19, thus enabling a tool head to be inserted within or removed from the tool handle without interference from the pawl.

In Figure 2, the improved handle is shown applied to a die head 24, the hub or throat 25 of which is slidably seated or received in the opening 5. To enable the head to be turned by the handle, its hub is provided with a series of circumferentially arranged grooves or slots 26 which are adapted to receive and be engaged by the pawl tooth 13. As shown, the slots are arcuate while the head of the tooth is substantially straight. This construction has the advantage that the rectangular edges of the tooth by biting into the surface of the slot inhibit movement of the head axially of the sleeve. While this construction is preferred, the handle will operate satisfactorily whether both slots and tooth head are arcuate or rectangular slots are employed so long as the surface engagement between the tooth and the confronting wall of the slot is adequate to prevent slippage when force is applied to the handle.

While particularly suited for use with die or other tool heads having cylindrical hubs, the ratchet handle of the present invention may also be employed with tool heads having hubs of various shapes. This is accomplished by the interposition of an adapter 27, such as illustrated in Figure 5, between the hub of the tool head and the sleeve 2 of the handle. All adapters for this purpose will possess in common an outer cylindrical surface having a series of circumferential grooves, to provide the necessary sliding fit within the sleeve and gripping surfaces for action of the pawl. The size and shape of the interior of the adapter will be determined by the configura-

tion of the hub of the tool head to which the handle is to be applied. In the illustrated embodiment the slot 28 has been given the hexagonal section of the hub of the standard form of wrench head.

After the components of the ratchet handle have been made and machined to the tolerances required to obtain the necessary sliding or rotating fits, they are assembled by inserting those parts housed in the upper and lower chambers 9 and 10 through the upper end of the upper chamber and the knob 20 through the slot 19. In order, the spring container 15 and the spring 14 are first inserted and the knob is next slipped into the slot 19. The pawl 12 is then slid into the upper chamber and into the inner opening of the knob, the latter then being attached to the pawl by the pin 21. Since the length of the pawl is normally greater than the diameter of the sleeve opening 5, a circular slot 29 is provided in the wall of the sleeve opposite the opening of the upper chamber through which the pawl and, if desired, the container 15 and spring 14 can be inserted in the housing.

In use, the stem 6 will occasionally provide sufficient leverage for the application of force through the sleeve 2 to a tool head. However, additional leverage will usually be required under normal operating conditions. For this purpose the length of the lever arm is increased by inserting a pipe, bar or other extension 30 in the opening in the handle provided by the lower chamber 10. Since the extension is comparatively smooth and would be slippery and difficult to handle under operating conditions, there is preferably attached to or mounted on its outer or lower end a grip 31 having a roughened outer or gripping surface 32.

It will be apparent from the foregoing detailed description of the invention that there has been provided a novel form of ratchet handle possessing numerous advantages. It should be understood that the form of the invention disclosed is merely an illustrative embodiment and that the invention includes all modifications that depart neither from its spirit nor the scope of the appended claims.

Having described my invention I claim:

1. A ratchet handle comprising a tool-seating sleeve, an elongated stem attached and disposed substantially normal to the axis of said sleeve, said stem having an axial bore extending into the opening in said sleeve, a reversible pawl seated in and movable axially of said bore, said bore being interrupted intermediate the ends thereof by a slot extending transversely through said stem, a collar riding in said slot and mounted on said pawl intermediate the ends thereof for imparting axial and rotative movement thereto, said collar being of greater dimension transversely of said stem than said bore, key means carried by said pawl and projecting above said collar in the direction of said sleeve opening, said stem being notched corresponding to said key means for receiving said key means and releasably locking said pawl in driving position in either driving direction, and said key means cooperating with said stem for retaining said pawl during reversal thereof in retracted position relative to said sleeve.

2. A ratchet handle comprising a tool-seating sleeve, an elongated stem attached and disposed substantially normal to the axis of said sleeve, said stem having an axial bore extending into the opening in said sleeve, a reversible pawl seated in and movable axially of said bore, said bore being

interrupted intermediate ends thereof by a slot extending transversely through said stem, a collar riding in said slot and mounted on said pawl intermediate ends thereof for imparting axial and rotative movement thereto, said collar being of greater dimension transversely of said stem than said bore, and key means carried by said pawl and engageable with said stem for releasably locking said pawl in driving position in either driving direction, said key means cooperating with said stem for retaining said pawl during reversal thereof in retracted position relative to said sleeve. 10

3. A ratchet handle comprising a tool-seating sleeve, an elongated stem attached and disposed substantially normal to the axis of said sleeve, said stem having an axial bore extending into the opening in said sleeve, a reversible pawl seated in and movable axially of said bore, said bore being interrupted intermediate ends thereof by a slot extending transversely through said stem, a 20 collar riding in said slot and mounted on said pawl intermediate ends thereof for imparting axial and rotative movement thereto, said pawl above said collar having substantially the same cross-section

as said bore and being slidably guided by said stem, said collar being of greater dimension transversely of said stem than said bore, and keys on and upstanding from said collar for engaging notches in said stem and releasably locking said pawl in driving position in either driving direction, said member cooperating with said stem for retaining said pawl during reversal thereof in retracted position relative to said sleeve.
